(57) **CLAIM**

The ornamental design for an adjustable paint roller frame, as shown and described.

DESCRIPTION

FIG. 1 is a top rear perspective view of an adjustable paint roller frame in a first operating position;

FIG. 2 is top front perspective view thereof;

FIG. 3 is a rear view thereof;

FIG. 4 is a front view thereof;

FIG. 5 is a right side view thereof;

FIG. 6 is a left side view thereof;

FIG. 7 is a top view thereof;

FIG. 8 is a bottom view thereof;

FIG. 9 is a top view of the adjustable paint roller frame in a second operating position;

FIG. 10 is a top view of the adjustable paint roller frame in a third operating position;

FIG. 11 is a top view of the adjustable paint roller frame in a fourth operating position;

FIG. 12 is a top view of the adjustable paint roller frame in a fifth operating position;

FIG. 13 is a top view of the adjustable paint roller frame in a sixth operating position;

FIG. 14 is a top view of the adjustable paint roller frame in a seventh operating position;

FIG. 15 is a top view of the adjustable paint roller frame in an eighth operating position; and,

FIG. 16 is a top view of the adjustable paint roller frame in a ninth operating position.

The portions shown in broken lines form no part of the claimed design.
